(57) **CLAIM**

The ornamental design for a “LED lamp for decoration,” as shown and described.

DESCRIPTION

FIG. 1 is a front perspective view of a LED lamp for decoration according to an embodiment;

FIG. 2 is a front view of the LED lamp for decoration of FIG. 1;

FIG. 3 is a rear view of the LED lamp for decoration of FIG. 1;

FIG. 4 is a left side view of the LED lamp for decoration of FIG. 1;

FIG. 5 is a right side view of the LED lamp for decoration of FIG. 1;

FIG. 6 is a top view of the LED lamp for decoration of FIG. 1;

FIG. 7 is a bottom view of the LED lamp for decoration of FIG. 1;

FIG. 8 is a front perspective view of the LED lamp for decoration of FIG. 1 shown in use with the light emitting part in diagonal line;

FIG. 9 is a front perspective view of a LED lamp for decoration according to another embodiment;

FIG. 10 is a front view of the LED lamp for decoration of FIG. 9;

FIG. 11 is a rear view of the LED lamp for decoration of FIG. 9;

FIG. 12 is a left side view of the LED lamp for decoration of FIG. 9;

FIG. 13 is a right side view of the LED lamp for decoration of FIG. 9;

FIG. 14 is a top view of the LED lamp for decoration of FIG. 9;

FIG. 15 is a bottom view of the LED lamp for decoration of FIG. 9; and,

FIG. 16 is a front perspective view of the LED lamp for decoration of FIG. 9 shown in use with the light emitting part in diagonal line.
